Specification for Design.

Patented July 12, 1921.

Application filed January 3, 1919. Serial No. 269,535. Term of patent 3½ years.

To all whom it may concern:

Be it known that I, CLARK NETTLETON, a citizen of the United States, residing at Seattle, in the county of King and State of Washington, have invented a new, original, and ornamental Design for a Flag, Pennant, Emblem, or Article of a Similar Nature, of which the following is a specification, reference being had to the accompanying drawing, forming part thereof.

The figure is a face view of a flag, pennant, emblem or article of a similar nature, showing my new design.

I claim:

The ornamental design for a flag, pennant, emblem, or article of a similar nature, as shown.

CLARK NETTLETON.
